United States Patent Office

Des. 179,362
Patented Dec. 4, 1956

179,362

TEXTILE

Leslie Tillett, New York, N. Y., assignor to Golding Bros.
Company, Inc., New York, N. Y., a corporation

Application August 31, 1956, Serial No. 42,802

Term of patent 3½ years

(Cl. D92—1)

The figure is a plan view of a textile showing my design.

The design unit is enclosed between the dot and dash lines, which unit is repeated in regular succession as indicated.

I claim:

The ornamental design for a textile, substantially as shown and described.
